ATTORNEY

UNITED STATES PATENT OFFICE.

WILLIAM U. GRIFFITHS, OF PHILADELPHIA, PENNSYLVANIA
FLUSH-TANK-VALVE-ACTUATING MECHANISM.

Serial No. 1,203,726.

Specification of Letters Patent.

Patented Nov. 7, 1916.

Application filed April 14, 1914. Serial No. 831,717.

To all whom it may concern:

Be it known that I, WILLIAM U. GRIFFITHS, a citizen of the United States, and a resident of Philadelphia, in the county of Philadelphia and State of Pennsylvania, have invented certain new and useful Improvements in Flush-Tank-Valve-Actuating Mechanism, of which the following is a specification.

10 My invention has for its object to simplify the construction of mechanism for operating the valve of a flush tank for controlling the flushing action of the latter and it consists in the combination and arrangement of parts as hereinafter more fully described and particularly set forth in the claim.

20 In the accompanying drawing I have illustrated one form of a convenient embodiment of my invention but it will be understood that changes in the details of construction within the scope of the claim may be made without departing from my invention.

25 In the drawings:—Figure 1 is a view partly in front elevation and partly in section; and Fig. 2 is a view showing a part of the flush tank in transverse section and certain of the operating mechanism in elevation.

30 Referring to the drawings, 1 designates a water closet bowl supported upon a floor or other support 2 and 3 designates a soil pipe.

35 4 designates a pipe for supplying water to the flush tank 5.

6 designates a flush pipe for conveying water from the tank 5 to the upper part of the bowl 1 for flushing and cleansing the same. The upper end of the pipe 6 communicates with the lower end of one of the legs of a siphon 7. The longer leg of the siphon is provided with a port 8 closed by a valve 9 pivoted at 10.

45 For the purpose of opening the valve 9 I have provided a rod or bar 12 which extends across the flush tank 5 in the manner quite clearly shown in Fig. 2 of the drawings, which rod is pivotally mounted in bearings on the walls of said tank as shown at 13 and 50 14. The rod is provided with an offset or crank portion 15 to which the upper end of a link connection 16 is connected, the lower end thereof being connected at 17 to the valve 9. One end of the operating rod or bar 12 extends beyond the side of the flush

tank and is provided with a handle 20 by means of which the rod 12 may be turned and rotated in either direction. In the normal position of the parts the handle 20 preferably projects downwardly in the manner shown in full lines in Fig. 1 while the crank portion 15 of the said rod extends in a direction toward the point of connection of the link 16 with the valve 9 at 17 so that the said crank and link connection 16 are in substantial alinement as is shown in the full and dotted lines in Fig. 1 of the drawings. When the handle 20 is turned in either direction, that is toward the left or toward the right, the crank is correspondingly turned so that the link connection 16 is lifted to cause the valve 9 to be opened. In the drawing I have illustrated the handle, in dotted lines, as having been turned toward the left, the resulting positions of the handle 9 and link 16 being also shown in dotted lines. The valve may be turned toward the right if desired and in either case may be turned so as to make a complete revolution, the rod or bar and its crank also making a complete revolution. It is not necessary, however, that the handle and rod or bar be turned completely around.

55 When the valve is opened the water rushes through the port or opening 8 and starts siphonic action so that when the valve 9 closes the water continues to flow through the siphon and through the flush pipe 6 to the bowl 1 in known manner. As the water in the tank 5 empties therefrom the ball float 21 moves downwardly with the water to permit the opening of a valve at 22 to permit water to flow from the supply pipe 4 into the tank 5.

60 When the water has been discharged through the siphon 7 from the tank 5 the siphonic action is broken so that the tank immediately begins to fill by reason of the water flowing thereto from the discharge opening 23 from the supply pipe 4. It continues to fill until the float ball 21 has been raised to a height sufficient to cause the cam 24 upon the inner end of the lever 25 supporting the said ball to act upon the valve 22 to close the same and thus prevent further flow of the water from the pipe 4 into the tank 5.

65 It will be seen that applicant has provided a very simple construction of means for operating the valve 9 and that such

means contains very few parts with the result that there is little likelihood of the mechanism getting out of order and needing repair.

5. I claim:

The combination of a flush tank valve, a rotatable member having an arm, a link having connection with the said valve and with the said arm, the said link and arm being

10 normally in substantial alinement, and

means for rotating said member in either direction for opening the said valve.

In testimony that I claim the foregoing as my invention, I have hereunto signed my name this fourth day of April, A. D. 1914. 15

WILLIAM U. GRIFFITHS.

In the presence of:

HORACE D. REEVE,

CYRUS N. ANDERSON.
